and Leonard John Lambourn, Erdington, Eng-
land, assignors to Dunlop Tire and Rubber
Corporation, Buffalo, N. Y., a corporation of
New York

Application October 31, 1938, Serial No. 80,794
In Great Britain June 14, 1938

Term of patent 14 years

To all whom it may concern:

Be it known that we, Frank George William King and Leonard John Lambourn, each a subject of the King of Great Britain, and residents of "Guy Harlings", Wyvern Road, Sutton Coldfield, county of Warwick, England, and of Poppy Lane, Erdington, county of Warwick, England, respectively, have invented a new, original, and ornamental Design for Tires, of which the following is a specification, reference being had to

the accompanying drawing, forming a part thereof.

Fig. 1 is a perspective view of a section of a tire showing our new design.

Fig. 2 is a plan view thereof.

We claim:

The ornamental design for a tire, as shown.

FRANK GEORGE WILLIAM KING.
LEONARD JOHN LAMBOURN.
